UNITED STATES PATENT OFFICE.

JOHN L. FOGLE AND VICTOR C. FOGLE, OF PUEBLO, COLORADO; SAID JOHN L. FOGLE
ASSIGNOR TO SAID VICTOR C. FOGLE.

PORTABLE TOWER.

1,095,391.

Specification of Letters Patent.

Patented May 5, 1914.

Application filed September 9, 1913. Serial No. 788,892.

To all whom it may concern:

Be it known that we, JOHN L. FOGLE and VICTOR C. FOGLE, citizens of the United States of America, and residents of Pueblo, in the county of Pueblo and State of Colorado, have invented certain new and useful Improvements in Portable Towers, of which the following is a specification.

This invention relates to portable towers and an object of the invention is to provide an apparatus for elevating and lowering the section of a tower, means being provided for bracing the said tower and making the same comparatively rigid while affording the collapsible feature so necessary to compactness, when the same is stored.

A further object of this invention is to provide novel means for permitting the adjustment of the corners of the skeleton tower in order that a lazy tong construction of the side thereof may move as the tower is elevated, thus causing the said tower or the corners thereof to approach and recede according to the direction of movement of the tower operating mechanism.

A still further object of this invention is to provide a tower in which the corner posts automatically adjust themselves and in which the structure is strong and efficient as well as comparatively inexpensive to produce and maintain.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a view in elevation of a tower embodying the invention; Fig. 2 illustrates a view in elevation of the cage and the platform associated therewith; Fig. 3 illustrates a view in elevation of the tower in its collapsed position; Fig. 4 illustrates a top plan view of the cage hoisting mechanism, the cage being omitted; and Fig. 5 illustrates a detail view of the base for the telescopic tube. Fig. 6 illustrates a plan view of a collar constructed in accordance with our invention. Fig. 7, is an end view 55 of the same.

In these drawings 6 denotes a truck which may be of any appropriate type, here shown as of the horseless vehicle type, the same having a bed 7 carrying brackets 8 adapted to support the guide rods 9 which guide rods 60 are diagonally disposed and extend from the corners of the body toward the center thereof and are connected to a housing 10 which is adapted as a support for the telescopic tube, to be presently explained. The rods 9 65 act as guides for the collars 11, one collar being applied to each rod, so that said collar will slide under the influence of the elements to be presently explained, it being observed that the said collar has upstanding 70 ears 12 provided with apertures 13 for the reception of a pivotal pin 14.

The links or levers 16 are arranged in pairs at each side of the structure forming the tower, each pair of links being pivoted 75 together centrally and the lower pair of links being pivotally connected to ears 12 of the appropriate collar 11, each collar being slidable on a rod. The opposite ends of the links are pivoted to succeeding pairs of 80 links, the links of each succeeding pair being pivotally connected together at their centers to form a lazy tong construction, as shown in the drawing. As stated, each side of the tower has the same construction and 85 when the tower is elevated, it forms a frame-like support for a cage 17 which is mounted on a platform 18, the said cage being provided with a bridge 19 which is hinged to it and is designed for the purpose of being 90 applied to a window or door opening in the building to permit the escape of the occupants thereof. In order to add to the rigidity of the structure, the ends of the links which are pivoted together at their 95 outer ends are coupled to the ends of the pivoted links on the side by angular brackets 15, the angular brackets forming corners for the several sides of the tower.

The platform 18 has on its under side a 100 piston rod 20 which operates in a telescopic tube 21 and the said telescopic tube 21 is associated with a plurality of telescopic tubes which may be projected in the manner shown in Fig. 1 or may be nested as 105 shown in Fig. 3. The base or master tube 22 has a head 23 provided with an inlet pipe 24 and an outlet pipe 25, each of which is valved for the purpose of controlling the passage therethrough and fluid under pres- 110

sure being admitted through the pipe 24 will operate to force the tubes outward or upward, thus projecting the tubes and elevating the platform in the manner shown in Fig. 1, whereas the tower may be lowered by closing the passage of the pipe 24 and opening the pipe 25 to permit the escape of the pressure medium which has been admitted through the tube 24. The platform 18 has a series of plates 26 on its under surface provided with apertured ears 27 to which the upper ends of the levers or links are pivoted.

From an inspection of the drawing and consideration of the specification, it will be obvious that the operation of the tower depends solely upon the supply of fluid under pressure for elevating the said tower and the escape of the said fluid for lowering the said tower.

20 We claim—

In a portable tower, a base, brackets secured to the base, rods supported by the brackets and held in spaced relation with

the base, a collar on each of the rods, each of the collars having apertured lugs extending therefrom, lazy tongs supported between the lugs of the collars, a platform supported by one end of the lazy tongs, rods supported in spaced relation with the under side of the platform, collars operating on the rods, a means for forming a connection between the collars and the lazy tongs, whereby movement of the lazy tongs will produce a relative movement of the collars, a telescopic tube housed by the lazy tongs, a piston in the tube, and means for supplying air under pressure to the piston for operating the lazy tongs.

In testimony whereof, we hereunto affix our signatures in the presence of two witnesses.

JOHN L. FOGLE.
VICTOR C. FOGLE.
